BED RAIL BLANK

William R. Elrad, University Heights, Ohio

Application May 8, 1944, Serial No. 534,555

1 Claim. (Cl. 29—190)

1

This invention relates to bedroom furniture and particularly to blanks for bed rails and devices used for connecting them to bed ends.

The primary object of this invention is to provide a durable device which may be quickly and easily attached to the wood side rails of a bed.

Another object of this invention is to provide a hook connector member that may be quickly and easily stamped or blanked out of a single sheet of metal.

These and other objects of the invention will become apparent from a reading of the following specification and claim, together with the accompanying drawing, in which like parts are referred to and indicated by like reference characters and wherein:

Figure 1 is a side elevation of a bed rail embodying the instant invention and also a portion of a bed and showing the means for attachment thereto;

Figure 2 is a top plan view of the rail shown in the Figure 1;

Figure 3 is a portion of a bed rail showing the inner side of the connector member;

Figure 4 is a plan view of a blanked sheet of metal from which this connector is made;

Figure 5 is an orthographic view of the connector member and particularly showing the outside or normally visible portion thereof; and

Figure 6 is a view similar to that of Figure 5 but showing the inside or normally concealed portion of the connector member.

In the drawing there is shown a bed rail broadly indicated by the reference character 10 and a portion of a bed broadly indicated by the reference character 20. Each of these two elements will be described in detail and in the order just set forth.

The bed rail consists of a long board 11 on which there is mounted at each end the connector members 5 shown in the Figures 5 and 6. Each of the connector members 5 is formed of a single sheet of metal and consists of two plates or side panels 14 and 15 and an intermediate plate or panel 16. The three panels 14, 15 and 16 are distinct and separated by fold lines 17 which form the corners or vertical edges of the assembled rail 10. The members 5 are stamped out of durable metal sheets and each of the panels 14 and 15 has holes 12 punched therein for receiving the screws 19 or other means for fastening the connector members 5 to the board 11. The hooks 13 are formed and stamped out of the metal of the panel 15. If desired, and particularly if it is desired to have the hooks 13 project forward from the center of

2

the intermediate panel 16, the hooks 13 can be formed of the metal of the panel 14 and also of the intermediate panel 16, as is shown in the Figures 4 and 6. The space left in the panel 14 from which the material forming the hooks 13 is taken is indicated in the Figure 6 by the reference character 18. When properly bent, the side panels 14 and 15 are parallel. The hooks 13 project forward of the intermediate panel 16 and at approximately its vertical center. The boards 11 are recessed and formed with a flat tongue portion which fits between the plates 14 and 15 so that the surfaces of the connector members 5 and the board 11 will be flush and on the same plane. When mounted on the board 11, the panel 14 in which the holes 18 appear is on the inside of the bed and the visible smooth panel 15 is on the outside. When properly mounted on the board 11, the members 5 appear as shown in the Figures 1 and 2 and the projecting hooks 13 are then able to fit into the vertical slots 21 and engage the horizontal pins 22 of the bed 20.

It may be well to point out at this point that bed rails of the prior art consist of relatively small pieces of metal from which the hooks extend. They are generally inserted in a vertical slot cut in the end of the wood board or rail and are fastened therein by a few simple screws or pins. These had a tendency to work loose in the relatively softer wood and very often caused the board to split. The present invention, therefore, forms a much sturdier and more lasting construction and is very simple and easy to manufacture and mount.

Having thus described and illustrated the invention, it should be understood that the invention as shown is illustrative only and is not to be considered in a limited sense, as other forms or modifications of the invention can be made within the scope of the appended claim.

I claim:

A sheet metal blank for a bedstead bracket consisting of an elongate plane body having top, bottom and end edges, said body having a pair of spaced transverse fold lines extending completely across the blank intermediate said end edges, and said body having a hook-defining portion partially blanked therefrom, said hooked-defining portion having its inner side edge integrally connected to the body and defined by a fold line disposed between said transverse fold lines and terminating spaced from the top and bottom edges of the blank, and said hook defining portion having its opposite outer free side edge terminating between one of said pair of transverse fold lines

and one of the end edges of said blank, said blank being adapted to be bent into substantially U-form to provide a pair of spaced side walls and an end wall for engaging the end and side walls of a bedstead rail, and with said hook defining portion being bent outwardly from the end wall at substantially right angles thereof for engagement with a hook receiving portion of a bed end part.
